UNITED STATES PATENT OFFICE.

JOHN W. DIXON, OF MAYWOOD, ILLINOIS.

MACHINE FOR APPLYING BINDING STRIPS.

Application filed September 2, 1924. Serial No. 735,231.

To all whom it may concern:

Be it known that I, JOHN W. DIXON, a citizen of the United States, residing at Maywood, in the county of Cook and State 5 of Illinois, have invented certain new and useful Improvements in Machines for Applying Binding Strips, of which the following is a specification.

This invention relates to a machine primarily designed to automatically perform the operations necessary in applying a metallic binding or edging strip to calendars, posters or the like, and the object of the invention is to so construct and arrange the 10 various mechanisms required in folding and compressing the binding strip that they will rapidly and certainly fold and compress the strips without the need for manipulation by the operator other than that required in 15 feeding the machine and removing the completed product therefrom.

In operating the machine of the present invention, a binding strip folded in channel formation is first fed into the machine and 20 thereafter the edge of the paper calendar or the like is inserted into the channel. The first operation required in the machine is that of folding over one edge of the metallic binding strip with the inserted paper, 25 thereafter reversing the position of the strip within the machine and finally compressing the strip to maintain the fold with the edge of the paper interfolded into the metallic strip. Various portions of the present machine are designed to automatically perform 30 the several operations above indicated in the proper sequence, and the invention consists in the combinations of such mechanisms constructed and mounted in the manner herein- 35 after explained.

In the drawings:

Figure 1 is a top or plan view of the machine with the paper table removed to better display the underlying mechanism;

Fig. 2 is a sectional view taken on line 2-2 of Fig. 1, looking in the direction of the arrows;

Fig. 3 is an enlarged detail showing the adjustable stops for positioning the binding strips;

Fig. 4 is a sectional view taken on line

4-4 of Fig. 1, looking in the direction of the arrows, and with the folding mechanism in normal or open position;

Fig. 5 is a view taken on line 5-5 of Fig. 1, with the parts in the normal position;

Fig. 6 is a view taken on line 6-6 of Fig. 1, with the parts in the normal position;

Fig. 7 is an end view of the machine showing a portion of the frame broken 60 away to better reveal the mechanism;

Fig. 8 is a sectional detail of the spring bearing for the folder shaft; and

Figs. 9, 10, 11, 12 and 13 are a series of 65 details of the folding and clamping mechanisms in various positions during the cycle of operations performed by the machine.

The machine as a whole is carried by a structure comprising end frames 20 of skeletonized formation which are suitably connected by cross rails 21 to afford the necessary ruggedness and rigidity. Above the frame is mounted a flat table 22 supported 70 near its forward end by brackets 23 which hold it in elevated relation to the folding and clamping mechanisms which are located in front of the table. The forward edge 24 of the table is downwardly sloped to afford a slide for the forward edges of the calendar blanks which are stacked upon the table. 75

Immediately in advance of the table, and at each end thereof are a pair of aligned stub shafts 25 one at each side of the machine. The two stub shafts are journaled within journal boxes 26 carried by the end 80 frames, which journal boxes are of slit formation each comprising a fixed lower section 27 and a yieldably mounted upper section 28, which latter is provided with vertical bores 29 through which are entered 85 headed guide posts 30 surrounded by the springs 31 which at their lower ends bear against shoulders 32. The lower ends of the posts are rigidly entered into the lower section of the journal boxes and held in fixed 90 relation by said screws 33, which arrangement serves to hold the upper section of the box tightly upon the associated stub shaft 25 while permitting a lifting thereof under spring tension in case of an emergency. 95

Each stub shaft has secured on its inner

end a disk 34 which occupies a position just inside of the proximate journal box, and the two disks are bridged by a folder bar 35 the acting face 36 of which lies in co-incident relation with the axis of the stub shafts. When in the normal position, indicated in most of the figures, the acting face will lie in a plane substantially co-incident with the plane of the forward or sloping edge of the table, so that paper sheets delivered from the table will slide freely over and lie upon the face of the folder. The folder bar immediately behind the acting face is beveled away as at 37 and the forward face 38 of the bar lies in right angle relation to the acting face 36, and in substantial co-incident relation with the transverse plane through the axis of the stub shafts.

Immediately in advance of the forward face of the folder bar is located a fixed cross bar 39 which bridges the space between the end frames. The bar lies in oblique relation and its upper edge 40 constitutes a continuation of the plane of the face 36 of the folder bar when in normal position. The upper edge of the fixed cross bar is shouldered at 41 and is provided with a plurality of transversely cut recesses 42 which receive and guide the rear or acting edges of a series of stop fingers 43 of angular formation, as shown in Fig. 3, which stop fingers are secured to a plate 44, which plate is provided with a pair of forwardly extending guide blocks 45 slidably mounted within cross channels 46 in an obliquely disposed bearing plate 47. Each of the guide blocks 45 is provided with an oblique guide slot 48 which receives an adjusting finger 49, which fingers are carried by a slide plate 50 which is guided to move transversely of the machine, so that movements imparted thereto will cause the fingers 49 to ride within the obliquely disposed slots 48 in the guide blocks 45 thereby imparting in and out movements of adjustment to the plate 44 which carries the stop fingers 43, so that the latter can be advanced toward or retracted from the fixed cross bar 39. This serves to adjust the position of the stop fingers with respect to the folder bar and to regulate the position to which the paper sheets will be fed. A suitable handle 51 pivoted at the point 52 and pivotally connected at 53 to the slide bar 50 serves to impart longitudinal movements thereto.

The bearing plate 47 has bolted thereon a compressor plate 54 the rear or acting edge of which projects beyond the bearing plate and the stops 43 and overlies the upper edge 40 of the fixed cross bar 39 which becomes, in effect, an anvil for co-operation with the edge of the compressor plate.

The bearing plate 47 has secured thereto at each end thereof a forwardly extending arm 55, which arms are journaled to brack-

ets 56 upstanding from the cross rail 21 of the frame, which arrangement affords a pivotal mounting for the entire structure comprising the stops 43 and associated parts as well as the compressor plate 54, so that movements of oscillation imparted to the bearing plate will serve to bring the rear or acting edge thereof into compressive relation with the edge 36 of the fixed cross bar, at a point immediately in advance of the folder bar.

Compressive movements are imparted by the provision of a downwardly extending arm 57 secured to the end of the bearing bar 47, which arm at its lower end is pivoted upon a pin 58 carried by an arm 59 which is clamped upon a rock shaft 60, which latter has clamped thereon an operating arm 61, which arm overlies a cam controlled arm 62 having near its center a pair of outstanding ears 63, through which ears an adjusting screw 64 is entered. The adjusting screw likewise passes through the rear end of the arm 61, so that by unclamping the arm from the rock shaft 60 and turning the adjusting screw, the relation of the arm to the shaft can be slightly varied.

The forward end of the cam arm 62 is pivoted upon the shaft 60, and the rear end carries a roller 65 which coacts with a cam 66 mounted upon a transversely extending cam shaft 67, so that movements of the cam will be imparted to the cam shaft and thence through the arm 57 to the compressor mechanism which will rock upon the bearings provided for the arms 55. The degree of movement, however, imparted to the clamping plate is so slight that it constitutes in effect a straight line up and down movement with respect to the underlying fixed cross bar.

The roller 65 is held in acting relation to the cam by provision of a link 68, the lower end of which is engaged by a spring 69 secured to the end frame at any suitable point.

The folder bar is revolved by provision of mechanism which is best shown in Fig. 7. The left hand stub shaft 25 is provided on its upper end with a pinion 70 in mesh with a segmental rack 71 journaled upon a stub shaft 72 outstanding from the end frame, and the rack 71 has pivoted thereto a link 73 of elbow formation, as indicated in dotted lines in Fig. 7, the rear lower end of which is clamped upon the outer end of a shaft 74 journaled upon the end frame. The inner end of the rock shaft 74 carries an arm 75 provided with an adjustable roller 76 which co-acts with a cam 77 on the cam shaft 67, so that rotation of the cam will cause an oscillating movement to be imparted through the link and gearing to the folder bar which will be moved through the positions indicated in Figs. 9, 11, 12 and 13.

That is to say, the bar will start from its normal or underlying position, indicated in Fig. 9, and be moved through approximately 180° to the overlying position, 5 shown in Fig. 11, and thereafter be moved back through the intermediate position indicated in Fig. 12 to the ultimate position shown in Fig. 13.

Bridging the space between the front 24 10 of the table, and the acting face of the folder bar is a bridge plate 78 across which the paper sheets slide when fed to position. It is necessary at the proper moment to retract the bridge plate to permit of the turning movement of the folder bar, and the mechanism for effecting this movement is 15 shown in Fig. 4. The bridge plate is mounted upon depending brackets 79 which are rigidly secured to curved arms 80 keyed 20 upon a rock shaft 81 which extends transversely of the machine at a point directly below the fixed cross bar and is supported within the rear end of journal brackets 82 which are carried by the front cross rail 21 25 of the machine frame.

The shaft 81 has also keyed thereon an obliquely depending arm 83 to the lower end of which is secured a spring 84 leading rearwardly to a suitable portion of the machine frame, which arrangement normally serves to hold the bridge plate in elevated relation, as indicated in full lines in Fig. 4, but permits the bridge plate to be retracted under tension, as indicated in dotted lines. 30 The bracket 79 has pivoted thereto a draw bar 85 which is slotted at its lower end 86 to embrace the cam shaft 67, and the lower end of the draw bar carries a roller 87 which engages a cam 88 on the cam shaft, so that 35 rotation of the cam, at the proper point, will retract the bridge plate in an oblique direction to afford a clearance for the folder bar.

A pair of stripper fingers 89 are provided, 40 which stripper fingers extend obliquely upward toward the rear with their rear ends in contact with the upper surface of the clamping plate 54. The stripper fingers are carried by a stripper bar 90 which is carried 45 between a pair of swinging arms 91 keyed upon opposite ends of a rock shaft 92 which is journaled within the journal brackets 82 in advance of the shaft 81, and the strippers are held normally in retracted 50 position through the action of a spring 93, the forward end of which engages an arm 94 keyed to and depending from the shaft 92. The stripping movement is imparted at the proper time to the stripper fingers 55 through the action of a draw rod 95, the forward upturned end of which engages a depending arm 96 on the shaft 92 and the rear end 97 of which is bifurcated to embrace the cam shaft 67. A roller 98 is provided 60 which engages a cam 99 on the cam

shaft, so that rotation of the latter will impart rocking movements to the shaft 92 and back and forth movements to the ends of the stripper fingers.

Above the stripper fingers is located a 70 forward deck 100 composed of a series of spaced plates 101 in aligned relation with their rear ends terminating at a point closely adjacent to the compressor plate 54.

The mechanism is driven by a motor 103 75 through the medium of a belt 104 which is carried around a pulley 105 mounted upon a main shaft 106, which latter carries a pinion 107 meshing with a spur gear wheel 108 freely mounted upon the cam shaft 67 near the right hand end thereof. Suitable clutch mechanism 109, which need not be described in detail, is operated by means of a draw rod 110 extending downwardly to a pivoted 80 foot pedal 111, which arrangement when operated serves to clutch the spur gear to the cam shaft.

Operation.

In use, the calendar sheets are stacked 90 upon the table 22 and the binding strips A are fed by hand into the machine in position to bring the bend of the binding strip in contact with the stop fingers immediately beneath the projecting edge of the clamping plate, as in Fig. 9. It will be noted that the binding strip A, as fed to the machine, is in the form of a strip folded lengthwise to provide a relatively narrow upper section and a relatively broad lower section 95 in obliquely disposed open relation to one another. The forward edge of a paper blank B is fed into the open channel of the strip and the binding operation is then 100 begun.

The formation of the cams on the cam shaft is such that the first movement imparted to the mechanism will be a lowering of the clamping plate, as in Fig. 10, which serves to compress the fold in the binding strip 110 to bring the sections thereof into parallel relation with one another. This initial lowering of the clamping plate takes place when the roller 65 is engaged by the elongated elevated portion of the cam 66.

The next movement imparted, will be a movement of revolution of the folder bar from the normal position to the position indicated in Fig. 11. This movement rolls the lower section of the binding strip over the rear edge of the clamping plate carrying the paper with it until the edge of the binding strip which initially occupied the lower position will overlie the companion edge of the binding strip after which the folder bar will retrace its movement, as in Fig. 12.

As the folder bar rolls back, the stripping fingers will be moved to the rear through the action of the cam which con- 130

trols these movements, and this will force the folded binding strip back from the edge of the clamping strip, which latter will then be lifted by the contact of the roller 65 with the elongated reduced portion of the cam 66 during which interval the paper sheet with the folded binding strip adhering thereto will spring back from the bent or flexed position, shown in Fig. 12, to a flat position and will again slide down beneath the now elevated clamping plate in preparation for the final compressive movement of the latter. This final clamping movement will be momentarily effected by contact of the roller 65 with the short hump at the end of the depressed portion of the cam 66. This final movement serves to tightly compress the folded binding strip with the edge of the paper interfolded into the metallic strip after which the clamping plate will again rise to permit of the removal of the bound paper sheet in preparation for a second operation. The arrangement and formation on the cam shaft is such as to automatically, and in proper timed relation, perform the several operations indicated, so that ordinarily it will be necessary only to feed the binding strips and the paper sheets and the several operations will thereafter be performed automatically.

The stub shafts which carry the folder bar being yieldably mounted within the spring journal boxes will automatically yield in the event any jamming occurs during the series of operations which is desirable in order to afford an element of safety against breakage.

The provision of the bridge plate 78 and the beveled formation of the folder bar, prevent the operator from inserting her fingers into a position in which they might be caught and injured by the movements of the folder bar, since it will be observed that even in the most advanced position of the folder bar, as indicated in Fig. 11, it will be impossible to injure the fingers.

I claim:

1. In a machine for applying binding strips to sheets, the combination of a stop for holding the sheet in position within the binding strip, a clamping plate for compressing the strip onto the sheet, a folding bar for folding one edge of the strip over the clamping device and thereafter returning to normal position, and means for stripping the sheet and folded strip from the clamping device, substantially as described.

2. In a machine for applying binding strips to sheets, the combination of stop members for holding the edge of a sheet within a binding strip of channel formation, a fixed and a movable clamping member for engaging the opposite side of the strip, a folding bar in position to engage the projecting edge of the binding strip, means for

moving one of the clamping members to clamping position, and means for thereafter revolving the folding bar with the engaged edge of the strip over one of the clamping members and then returning the folding bar to normal position, substantially as described. 70

3. In a machine for applying binding strips to sheets, the combination of stop members for holding the edge of a sheet within a binding strip of channel formation, a fixed and a movable clamping member for engaging the opposite side of the strip, a folding bar in position to engage the projecting edge of the binding strip, means for moving one of the clamping members to clamping position, means for thereafter revolving the folding bar with the engaged edge of the strip over one of the clamping members and then returning the folding bar to normal position, and means for thereafter releasing the clamping members momentarily and thereafter imparting a second clamping and releasing movement thereto, substantially as described. 75 80 85 90

4. In a machine for applying binding strips to sheets, the combination of a support for the sheets, a stop for positioning a channel-shaped binding strip with the interposed edge of a sheet, a pair of clamping members located on opposite sides of the positioned binding strip, one of said clamping members being movable, a folding bar mounted to move from a position adjacent one of the clamping members to a position beyond the other clamping member, means for imparting an initial clamping and releasing movement to the movable clamping member, means for thereafter imparting a final clamping and releasing movement to said movable clamping member, means for imparting a folding and return movement to the folding bar intermediate the initial and final movements of the clamping member, substantially as described. 100 105 110

5. In a machine for applying binding strips to sheets, the combination of a support for the sheets, a stop for positioning a channel-shaped binding strip with the interposed edge of a sheet, a pair of clamping members located on opposite sides of the positioned binding strip, one of said clamping members being movable, a folding bar mounted to move from a position adjacent one of the clamping members to a position beyond the other clamping member, means for imparting an initial clamping and releasing movement to the movable clamping member, means for thereafter imparting a final clamping and releasing movement to said movable clamping member, means for imparting a folding and return movement to the folding bar intermediate the initial and final movements of the clamping member, a stripping member, and means for imparting 115 120 125 130

a stripping movement to said member after the return movement of the folding bar and prior to the final movement of the movable clamping member, substantially as described.

5 6. In a machine for applying binding strips to sheets, the combination of a support for the sheets, a fixed clamping member and a movable clamping member, a folding bar normally intermediate the fixed clamping member and the support and mounted for movement from said position to a position beyond the movable clamping member, a bridge plate normally bridging the space between the support for the sheets and the 10 folding bar, means for imparting an initial clamping and releasing movement to the movable clamping member and a final clamping and releasing movement thereto, means for moving the folding bar to folding and return positions intermediate the initial and final movements of the clamping member, and means for retracting the bridge plate away from the path of movement of the folding bar prior to the beginning of 15 such movement and restoring the bridge plate to normal position after such movement from the folding bar, substantially as described.

7. In a machine for applying binding strips to sheets, the combination of a support for the sheets, a fixed clamping member and a movable clamping member, a folding bar normally intermediate the fixed clamping member and the support and mounted for movement from said position to a position beyond the movable clamping member, a bridge plate normally bridging the space between the support for the sheets and the folding bar, means for imparting an initial clamping and releasing movement to the movable clamping member and a final clamping and releasing movement thereto, means for moving the folding bar to folding and return positions intermediate the initial and final movements of the clamping member, means for retracting the bridge plate away from the path of movement of the folding bar prior to the beginning of such movement and restoring the bridge plate to normal position after such movement of the folding bar, a stripper, and means for advancing said stripper to stripping position after the return movement of the folding bar and prior to the final clamping movement of the movable clamping member, substantially as described.

8. In a machine for applying binding strips to sheets, the combination of a feeding table, a fixed clamping member in adjacent relation to the feeding table, a movable clamping member mounted for movement toward and from the fixed clamping member, a stop carried by the movable clamping member for holding the binding strips and sheets in aligned relation, a folding bar normally intermediate the movements of the clamping member, a bridge plate normally

ing bar normally presenting its folding face in aligned position to the face of the fixed clamping member, a mounting for the folding bar adapted to impart a movement of revolution thereto to carry the acting face of said folding bar beyond the edge of the movable clamping member, means for imparting an initial clamping and return movement and afterwards a final clamping and return movement to the movable clamping member, and means for imparting a folding and return movement to the folding bar intermediate the movements of the clamping member, substantially as described.

9. A machine for applying binding strips to sheets, the combination of a feeding table, a fixed clamping member in adjacent relation to the feeding table, a movable clamping member mounted for movement toward and from the fixed clamping member, a stop carried by the movable clamping member for holding the binding strips and sheets in aligned relation, a folding bar normally presenting its folding face in aligned position to the face of the fixed clamping member, a mounting for the folding bar adapted to impart a movement of revolution thereto to carry the acting face of said folding bar beyond the edge of the movable clamping member, means for imparting an initial clamping and return movement and afterwards a final clamping and return movement to the movable clamping member, means for imparting a folding and return movement to the folding bar intermediate the movements of the clamping member, a stripper mounted to move across the rear surface of the movable clamping member, and means for imparting a stripping movement to said stripper after the return movement of the folding bar and prior to the final movement of the movable clamping member, substantially as described.

10. A machine for applying binding strips to sheets, the combination of a feeding table, a fixed clamping member in adjacent relation to the feeding table, a movable clamping member mounted for movement toward and from the fixed clamping member, a stop carried by the movable clamping member for holding the binding strips and sheets in aligned relation, a folding bar normally presenting its folding face in aligned position to the face of the fixed clamping member, a mounting for the folding bar adapted to impart a movement of revolution thereto to carry the acting face of said folder beyond the edge of the movable clamping member, means for imparting an initial clamping and return movement and afterwards a final clamping and return movement to the movable clamping member, means for imparting a folding and return movement to the folding bar intermediate the movements of the clamping member, a bridge plate normally

bridging the space between the feeding table and the folding bar, and means for retracting the bridge plate prior to the folding movement of the folding bar and restoring the bridge plate to normal position thereafter, substantially as described.

11. A machine for applying binding strips to sheets, the combination of a feeding table, a fixed clamping member in adjacent relation to the feeding table, a movable clamping member mounted for movement toward and from the fixed clamping member, a stop carried by the movable clamping member for holding the binding strips and sheets in aligned relation, a folding bar normally presenting its folding face in aligned position to the face of the fixed clamping member, a mounting for the folding bar adapted to impart a movement of revolution thereto to carry the acting face of said folding bar beyond the edge of the movable clamping member, means for imparting an initial clamping and return movement and afterwards a final clamping and return movement to the movable clamping member, means for imparting a folding and return movement to the folding bar intermediate the movements of the clamping member, a stripper mounted to move across the rear surface of the movable clamping member, means for imparting a stripping movement to said stripper after the return movement of the folding bar and prior to the final movement of the movable clamping member, a bridge plate normally bridging the space between the feeding table and the folding bar, and means for retracting the bridge plate prior to the folding movement of the folding bar and restoring the bridge plate to normal position thereafter, substantially as described.

12. In a machine for applying binding strips to sheets, the combination of a feeding table, a fixed clamping member in proximate relation to said table, a pivotally mounted clamping plate in co-acting relation to the said fixed clamping member, an adjustable stop movable with said movable clamping plate and limiting the movement of the sheet and binding strip into the space between the fixed clamping member and movable clamping plate, a folding bar normally standing in proximate relation to the fixed clamping member and mounted to be swung over into a position beyond the edge of a movable clamping plate, means for imparting a swinging clamping movement and return to the movable clamping plate, and means for imparting

ing folding and return movements to the folding bar, substantially as described.

13. In a machine for applying binding strips to sheets, the combination of a feeding table, a fixed clamping member in proximate relation to said table, a pivotally mounted clamping plate in co-acting relation to the said fixed clamping member, an adjustable stop movable with said movable clamping plate and limiting the movement of the sheet and binding strip into the space between the fixed clamping member and movable clamping plate, a folding bar normally standing in proximate relation to the fixed clamping member and mounted to be swung over into a position beyond the edge of the movable clamping plate, means for imparting a swinging clamping movement and return to the movable clamping plate, means for imparting folding and return movements to the folding bar, a bridge plate normally bridging the space between the feeding table and the folding bar, and means for retracting and afterwards restoring said bridge plate to afford clearance for the movement of the folding bar, substantially as described.

14. In a machine for applying binding strips to sheets, the combination of a feeding table, a fixed clamping member in proximate relation to said table, a pivotally mounted clamping plate in co-acting relation to the said fixed clamping member, an adjustable stop movable with said movable clamping plate and limiting the movement of the sheet and binding strip into the space between the fixed clamping member and movable clamping plate, a folding bar normally standing in proximate relation to the fixed clamping member and mounted to be swung over into a position beyond the edge of the movable clamping plate, means for imparting a swinging clamping movement and return to the movable clamping plate, means for imparting folding and return movements to the folding bar, a bridge plate normally bridging the space between the feeding table and the folding bar, means for retracting and afterwards restoring said bridge plate to afford clearance for the movement of the folding bar, and a plurality of stripper fingers mounted to move across the reverse face of the movable clamping plate, and means for imparting to said stripper fingers a stripping movement after the return movement of the folding bar, substantially as described.

JOHN W. DIXON.
